United States Patent Office

Des. 232,709
Patented Sept. 10, 1974

232,709

BOAT

Avery Marrin, Tulsa, Okla., assignor to
Clam Corporation, Tulsa, Okla.

Filed July 20, 1972, Ser. No. 273,541

Term of patent 14 years

Int. Cl. D12—6

U.S. Cl. D12—62

FIG. 1 is a top view of the boat showing my new design.

FIG. 2 is a side elevational view of one side thereof, the opposite side being a mirror image of the side shown.

FIG. 3 is a bottom view thereof.

FIG. 4 is a rear elevational view thereof.

FIG. 5 is a front elevational view thereof.

I claim:

The ornamental design for a boat, substantially as shown and described.
